(57) **CLAIM**

I claim the ornamental design for a shoe, as shown and described.

DESCRIPTION

FIG. 1 is a front elevational view of a shoe showing my new design;

FIG. 2 is a rear elevational view of the shoe shown in FIG. 1; FIG. 3 is a right side elevational view of the shoe shown in FIG. 1;

FIG. 4 is a left side elevational view of the shoe shown in FIG. 1;

FIG. 5 is a top plan view of the shoe shown in FIG. 1;

FIG. 6 is a bottom plan view of the shoe shown in FIG. 1; and, FIG. 7 is a front perspective view of the shoe shown in FIG. 1.
